UNITED STATES PATENT OFFICE

136,173

DESIGN FOR A MAP

Paul von Rohl, St. Paul, Minn.

Application June 10, 1943, Serial No. 110,423

Term of patent 14 years

To all whom it may concern:

Be it known that I, Paul von Rohl, a citizen of the United States, residing at St. Paul, in the county of Ramsey and State of Minnesota, have invented a new, original, and ornamental Design for a Map, of which the following is a specification, reference being had to the accompanying drawing, forming part thereof.

Figure 1 is a top plan view of a map, showing my new design;

Figure 2 is a top perspective view of the same; Figure 3 is a perspective view of the same in folded position; and

Figure 4 is a side elevational view of the same in folded position.

I claim:

The ornamental design for a map, as shown.

PAUL VON ROHL.
